UNITED STATES PATENT OFFICE

LUKE C. MAMBOURG, OF LANCASTER, OHIO, ASSIGNOR TO LIBBEY-OWENS-FORD GLASS COMPANY, OF TOLEDO, OHIO, A CORPORATION OF OHIO

WIDTH MAINTAINING MEANS FOR SHEET GLASS APPARATUS

Application filed October 30, 1926. Serial No. 145,210.

The present invention relates to sheet glass apparatus, and has more particular reference to improved means for preventing the narrowing of a sheet being drawn from a mass of molten glass.

An important object of the invention is to provide improved means at both edges of the sheet being drawn for creating an edge relatively viscous and sufficiently strong to prevent narrowing of the sheet.

Another important object of the invention is to provide improved width maintaining means of the above character, whereby the thickness of the edges formed on the sheet may be varied as desired and effectively controlled.

A further object of the invention is to provide improved width maintaining means of the above character, including a slotted yieldable member so constructed as to permit the continuous circulation of a cooling medium therethrough.

A still further object of the invention is to provide improved width maintaining means of the above character, including a yoke having a slot for receiving the edge portion of the sheet, and means for increasing or decreasing the width of said slot to vary the thickness of the edge being formed on said sheet.

Still another and important object of the invention is to provide improved width maintaining means of the above character, including a yoke arranged about each edge of the sheet and provided with spaced yieldable jaws engaging said sheet, means for supporting said yoke, and means for contracting and expanding said jaws whereby to vary the thickness of the edge being formed on said sheet.

Still another object of the invention is the provision of means for adjustably mounting the improved width maintaining means.

Other objects and advantages of the invention will become more apparent during the course of the following description when taken in connection with the accompanying drawings.

In the drawings forming a part of this application and wherein like numerals are em-

ployed to designate like parts throughout the same,

Fig. 1 is a transverse sectional view of sheet glass drawing apparatus showing associated therewith improved width maintaining means constructed in accordance with the present invention.

Fig. 2 is a detail section taken on line 2—2 of Fig. 1.

Fig. 3 is a fragmentary view of a portion of the sheet glass drawing apparatus showing one of the improved width maintaining devices in section.

Fig. 4 is an inner edge elevation of one of the improved width maintaining devices.

Fig. 5 is a fragmentary section of another type of sheet glass drawing apparatus in connection with which the present invention may be used.

Fig. 6 is a view somewhat similar to Fig. 1, but showing the width maintaining device in tilted position.

Fig. 7 is a detail top plan view of the means for adjustably supporting the width maintaining device.

Fig. 8 is a top plan view of a slightly modified form of the present invention, and

Fig. 9 is a transverse sectional view taken substantially on line 9—9 of Fig. 8.

In drawing sheet glass in accordance with the Colburn Patent No. 1,248,809, granted December 4, 1917, a draw pot 10, containing a mass of molten glass 11, is provided, and a sheet 12 is drawn from the said mass initially in the vertical plane for a short distance, after which it is deflected over a bending member 13 into the horizontal plane. The glass is then run over a flattening table and through an annealing leir which have not been shown.

In accordance with the Colburn machine, a pair of rotatable knurled rollers are provided at both edges and on either side of the sheet to form an edge thereon sufficiently viscous to prevent narrowing of the sheet to an appreciable extent. It is an aim of the present invention to substitute for these knurled rollers, a slotted yieldable member or yoke to obviate the necessity for the driving mechanism and to also cut down the

amount of waste that has heretofore been had.

In accordance with the present invention, there is provided at each edge of the sheet 12 adjacent the source 11, a stationary supporting member or yoke 14, comprising side portions 15 and 16 and a connecting bight portion 17. The yoke 14 is supported upon a bar or the like 18 carried by suitable supporting structure 19, which will be more specifically hereinafter described.

Arranged within the stationary yoke 14, is a second yoke or slotted member designated in its entirety by the numeral 20 and comprising spaced yieldable jaws 21 and 22 and a connecting bight portion 23. The spaced jaws 21 and 22 form a slot 35 for receiving the edge portion 12' of the sheet 12.

Carried by the upper and lower ends of the inner yoke 20 are the rearwardly extending horizontal ears 24 and 25, pivotally secured to the stationary yoke 14 and supporting bar 18 respectively, by means of pins 26 and 27. With such a construction as described, it will be seen that the inner yoke or slotted member 20 will be permitted to swing laterally relative to the supporting yoke 14.

The slotted member 20 is preferably hollow to permit the continuous circulation of a suitable cooling medium therethrough, and this medium is introduced into the member through a supply pipe 28 adjacent the lower end thereof. The cooling medium, after it becomes heated, will normally rise within the member 20 and pass outwardly through the pipe 29.

One of the important features of the present invention, is the provision of means whereby the thickness of the edge being formed on the sheet may be varied as desired and effectively controlled. This is accomplished by providing means for contracting and expanding the jaws 21 and 22 of the member 20 whereby to increase or decrease the width of the slot 35.

In order to expand the jaws 21 and 22, there is carried by each of the sides 15 and 16 of the yoke 14, a pair of vertically spaced adjusting screws 30 and 31. These adjusting screws pass loosely through the said sides 15 and 16 of the stationary yoke and are threadedly received within bosses 32 formed on the jaws 21 and 22. Thus, in order to increase the width of the slot 35 it is simply necessary to thread the adjusting screws 30 and 31 into the bosses 32, and when this is done the said jaws will be caused to move outwardly. This increasing of the distance between the said jaws will tend to necessarily increase the thickness of the edge being formed on the sheet.

In order to contract the yieldable jaws 21 and 22 and thus reduce the width of the slot 35, there are provided adjusting screws 33

and 34 arranged at each side of the yoke 14 and between the adjusting screws 30 and 31. The adjusting screws 33 and 34 are threaded through the sides 15 and 16 of the said stationary yoke and simply bear against the yieldable jaws 21 and 22. To move the yieldable jaws closer together, it is only necessary to first loosen the screws 30 and 31 and subsequently thread the screws 33 and 34 inwardly. These screws bearing against the yieldable jaws will tend to force them closer together, thereby reducing the width of the slot 35 and the thickness of the edge being formed on the sheet.

The operation of the machine with these width maintaining devices will be slightly different than with the knurled rollers described above. The edge of the glass sheet being drawn up will be pulled through the slot 35 and because of the inherent tendency of molten glass, a certain amount of frictional resistance will be had between the moving glass and the jaws 21 and 22 of the member 20. This frictional retardation encourages a lowering of the temperature of the glass which is further accelerated by means of the cooling medium. The cooling is not so severe that the glass becomes set, but it is of such a nature that the edge of the glass will be comparatively viscous to the main body of the glass, thus being sufficiently strong to prevent the glass sheet from narrowing at its base.

While the present invention has been described hereinabove in connection with one particular type of process, yet it is to be understood that its use is not to be restricted to any one specific form of sheet glass apparatus, inasmuch as it may be used just as satisfactorily in other types of processes.

For instance, in Fig. 5 has been disclosed a portion of the so-called Foucault process for drawing sheet glass and wherein the glass is melted in an ordinary hearth 36. This hearth communicates by an opening 37 with a small reservoir 38, which receives and is constantly being replenished with molten glass 39 from the furnace. A damper 40 of refractory material is provided for regulating and closing an opening 41 to allow more or less heat to pass from the hearth to the reservoir 38.

A block or deputer 42 of refractory material is arranged in the upper part of said reservoir 38 and is provided with a vertical slot 43 through which the glass is forced upwardly under hydrostatic pressure.

The sheet 44 is then drawn upwardly and passes between vertically spaced pairs of rolls 45, through an annealing apparatus 46 having the shape of a vertical casing. The sheet, after becoming set, is then cut transversely into sheet form as will be appreciated.

In this form of the invention, the improved width maintaining devices are positioned be-

tween the annealing apparatus 46 and block 42. Of course, it will be understood that the block or deputer 42 may be eliminated if desired.

5 The supporting structure 19 may be of any suitable construction, but is preferably of such a type that the width maintaining devices may be readily adjusted relative to sheet 12. As shown, the supporting bar 18
 10 is secured at its outer end to a substantially rectangular plate 47 slideable within a guide-way formed by the spaced guide blocks 48 and 49. The side edges of the plate 47 are bevelled as at 50 to snugly fit corresponding-
 15 ly undercut bevelled edges of the guide blocks 48 and 49. With such a construction, the width maintaining devices can be readily moved closer to or away from the sheet 12 as preferred and can be secured in the de-
 20 sired position by means of set screws 51 which pass through the guide block 48 and bind against the plate 47.

The guide blocks 48 and 49 are pivotally mounted as at 52 to a bearing member 53 pro-
 25 vided with a depending screw-threaded rod 54 which is received within the central bearing portion 55 formed on the plate 56. The plate 56 rests upon the upper surface of a channel iron 57 and the depending bearing
 30 portion 55 thereof operates within a longitudinally extending slot formed therein. The plate 56 is secured against accidental move-
 35 ment by means of bolts 58 which pass through and also operate in slots formed in the channel iron 57, said bolts carrying at their lower ends a second plate 59 which abuts the bottom of the channel iron. A nut 60 is threaded on the rod 54 and rests upon the plate 56 so that the width maintaining device
 40 can be readily raised and lowered relative to the mass of molten glass 11, by simply ro-
 45 tating the nut 60 in the desired direction.

Carried by the bearing member 53 are out-
 45 wardly and oppositely directed lugs 61 through which are threaded vertical adjusting screws 62 which contact with the bottom of the guide block 49. Thus, when it is de-
 50 sired to adjust the angle of the width main-
 55 taining device relative to the sheet 12, it is
 60 only necessary to first loosen one of the ad-
 65 justing screws 62 and subsequently tighten up on the opposite screw whereupon the guide blocks 48 and 49 will be rocked about their pivots 52 whereby to change the angle of the width maintaining device. In Fig.
 70 6, the width maintaining device has been shown at an angle relative to the sheet, and by tilting the devices in this manner, they will serve to grip and direct the edges of the sheet
 75 upwardly and outwardly, thereby stretching the sheet transversely whereby to permit a relatively wider sheet to be drawn from a given width of draw pot.

In order to move the width maintaining
 80 devices horizontally and longitudinally of

the draw pot, the bolts 58 can be loosened and the plate 56 slid along on the channel iron 57. With such a supporting structure, as described hereinabove, the width maintaining devices can be moved towards and away
 85 from the sheet, raised or lowered relative to the draw pot, moved horizontally and longitudinally of the draw pot, and tilted upwardly or downwardly in the glass.

In Figs. 8 and 9, wherein has been shown a slightly modified form of the present invention, it will be noted that the slot 35 in the yoke or member 20, is wider at its lower end than at its upper end. In other words, the slot tapers upwardly or narrows gradually until at its upper end it is of a width substantially the same thickness as the central body of the sheet being drawn. With such an arrangement, a comparatively large amount of molten glass will be drawn up into the slot initially, and this mass will be gradually reduced in thickness so that as the edge portion leaves the upper end of the slot, the sheet will be substantially the same thickness throughout its entire width. It is believed that with such a construction, the width of the sheet can be materially increased.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

Claims:

1. In sheet glass apparatus, the combina-
 105 tion with means for drawing a sheet from a bath of molten glass, of means for maintaining said sheet to width, including a slotted member having resilient portions embracing the sheet edge.

2. In sheet glass apparatus, the combina-
 110 tion with means for drawing a sheet from a bath of molten glass, of means for maintaining said sheet to width, including a slotted member embracing the sheet edge, and means for deforming said member to vary the width of the slot therein.

3. In sheet glass apparatus, the combina-
 115 tion with means for drawing a sheet from a bath of molten glass, of means for maintaining said sheet to width, including a slotted member having a pair of spaced jaws embrac-
 120 ing the sheet edge, and means for deforming said member to vary the distance between said jaws.

4. In sheet glass apparatus, the combina-
 125 tion with means for drawing a sheet from a bath of molten glass, of means for maintaining said sheet to width, including a slotted member having a pair of spaced jaws embrac-
 130 ing the sheet edge, means for deforming said member to vary the distance between

said jaws, and means for internally cooling the jaws.

5. In sheet glass apparatus, the combination with means for drawing a sheet from a bath of molten glass, of means for maintaining said sheet to width, including a slotted member having resilient portions embracing the sheet edge, and means for effecting contraction and expansion of said resilient portions to vary the width of the slot in said member.

6. In sheet glass apparatus, the combination with means for drawing a sheet from a bath of molten glass, of means for maintaining said sheet to width, including a substantially U-shaped member having a pair of spaced resilient jaws embracing the sheet edge, and means for effecting contraction and expansion of said jaws to vary the distance therebetween.

7. In sheet glass apparatus, the combination with means for drawing a sheet from a bath of molten glass, of means for maintaining said sheet to width, including a substantially U-shaped member having a pair of spaced resilient jaws embracing the sheet edge, means for effecting contraction and expansion of said jaws to vary the distance therebetween, and means for internally cooling said jaws.

8. In sheet glass apparatus, the combination with means for drawing a sheet from a bath of molten glass, of means for maintaining said sheet to width, including a yoke, and a deformable member arranged within and carried by said yoke and having portions thereof embracing the sheet edge.

9. In sheet glass apparatus, the combination with means for drawing a sheet from a bath of molten glass, of means for maintaining said sheet to width, including a yoke having spaced rigid side portions, a slotted member arranged within and carried by said yoke and having a pair of spaced jaws embracing the sheet edge, and means carried by the side portions of the yoke and engaging the jaws for deforming said slotted member to vary the width of the slot therein.

10. In sheet glass apparatus, the combination with means for drawing a sheet from a bath of molten glass, of means for maintaining said sheet to width, including a yoke having spaced rigid side portions, a slotted member arranged within and carried by said yoke and having a pair of spaced jaws embracing the sheet edge, means carried by the side portions of the yoke and engaging the jaws for deforming said slotted member to vary the width of the slot therein, and means for internally cooling said slotted member.

11. In sheet glass apparatus, the combination with means for drawing a sheet from a bath of molten glass, of means for maintaining said sheet to width, including a yoke having spaced rigid side portions, a slotted mem-

ber arranged within and carried by the yoke and having resilient portions embracing the sheet edge, and means carried by the side portions of said yoke and engaging said resilient portions for effecting contraction and expansion thereof to vary the width of the slot in said slotted member.

12. In sheet glass apparatus, the combination with means for drawing a sheet from a bath of molten glass, of means for maintaining said sheet to width, including a fixed substantially U-shaped member having spaced rigid side portions, a substantially U-shaped member arranged within the first member and having a pair of resilient jaws embracing the sheet edge, and means carried by the side portions of said first member and engaging the jaws of the second member for effecting contraction and expansion thereof.

13. In sheet glass apparatus, the combination with means for drawing a sheet from a bath of molten glass, of means for maintaining said sheet to width, including a substantially U-shaped member having rigid side portions, a second substantially U-shaped member arranged within the first member and including spaced jaws for receiving the sheet edge therebetween, and means carried by the side portions of the first member and engaging the jaws of the second member for moving said jaws toward and away from one another.

14. In sheet glass apparatus, the combination with means for drawing a sheet from a bath of molten glass, of means for maintaining said sheet to width, including a slotted member having a pair of jaws embracing the sheet edge, and means for deforming said member to vary the width of the slot between said jaws, said slot tapering from one end to the other.

Signed at Lancaster, in the county of Fairfield and State of Ohio, this 27th day of October, 1926.
